UNITED STATES PATENT OFFICE.

EMERSON P. JENNINGS, JR., OF LEHIGHTON, PENNSYLVANIA.

SHEET-DELIVERY DEVICE.

1,303,326.

Specification of Letters Patent.

Patented May 13, 1919.

Original application filed March 30, 1916, Serial No. 87,725. Divided and this application filed November 3, 1916. Serial No. 129,324.

To all whom it may concern:

Be it known that I, EMERSON P. JENNINGS, Jr., a citizen of the United States, residing at Lehighton, in the county of Carbon and State of Pennsylvania, have invented certain new and useful Improvements in Sheet-Delivery Devices, of which the following is a specification, reference being had therein to the accompanying drawings.

10 This invention relates to sheet delivery devices for printing presses and is designed more particularly for use in connection with the sheet feeding mechanism of the application filed by me March 30th, 1916, Serial 15 No. 87725, of which application the present application is a division.

The object of the invention is to provide a sheet delivering device which will operate in a highly efficient manner to take the sheet 20 from the press and deliver the same upon a suitable receiving table, or support; further it is an object of the invention to provide such a device which will be very simple in its construction and operation, and will be 25 positively operated in timed relation to other parts of the press to cause it to perform its functions.

It is also an object of the invention to provide such a device which will coöperate with 30 the other parts of a sheet feeding mechanism to automatically feed sheets of paper through the press.

Other objects of the invention will appear as the mechanism is described in detail.

35 In the accompanying drawings Figure 1 is a side elevation partly broken away of a printing press showing my invention applied thereto; Fig. 2 is a perspective detail view of the delivery grippers; Fig. 3 is a 40 sectional view of the gripping device showing one of the movable gripping jaws in detail; Fig. 4 is a sectional view taken vertically to the press showing the invention applied thereto in combination with other 45 sheet feeding instrumentalities, with the delivery grippers in their retracted position; and Fig. 5 is a similar view with the delivery grippers in engagement with the printed sheet.

50 In these drawings I have illustrated the invention as applied to a bed and platen press in which the form-bed moves in a horizontal line toward and from the platen, and

which is equipped with the sheet feeding devices of the above mentioned application, 55 but it will be understood that this particular type of press and sheet feeding mechanism is chosen for the purpose of illustration only and that the present invention may be applied to presses of different kinds, 60 either with or without automatic devices for feeding sheets to printing position.

As shown in the drawings the press as a whole comprises a main frame 1, consisting of side members spaced apart and tied together by tie rods and connecting devices and serving to support the various parts of the printing and feeding mechanisms. A normally stationary platen 2 is mounted near one end of the press and a form-bed 3 70 is mounted for movement toward and from the platen. In the particular type of press here shown the form-bed has combined therewith an inking drum 4. The combined form-bed and inking drum is provided at its 75 ends with trunnions mounted in guide blocks 5 which are slidably mounted in the guideways 6 formed in the side walls of the main frame 1. These trunnions are connected by pitmen 7 with crank wheels 8 80 which are here shown as gears meshing with pinions 9 on the shaft 10, to which power may be applied in any suitable manner.

The sheet feeding mechanism with which the press is equipped comprises a sheet separating device 11 having a separating member 12 which is suction operated and is actuated by suitable operating devices to turn the edge of the lowermost sheet of a pile 85 of sheets away from the pile and into a 90 position approximately parallel with the face of the platen 2. Coöoperating with the sheet separating device is a set of conveying grippers 13 which are mounted on a shaft 14 carried by brackets 15, which in 95 turn are mounted upon vertically reciprocating rack bars 16. These rack bars also carry cam plates 17 which impart turning movement to the sheet separating member 12. The rack bars 16 mesh with gears 18 100 mounted on a transverse shaft 19 and provided with a pinion 20 which meshes with a horizontal rack bar 21 connected at one end to the form-bed 3, preferably by connecting it with one of the slide blocks 5. 105 The conveying grippers 13 engage the down-

turned edge of the sheet and move the same into printing position on the face of the platen, where they release the same and continue their movement to a point below the platen and out of the path of the form-bed. The platen grippers 22 are moved into engagement with the sheet to hold it snugly against the face of the platen when taking the impression and these platen grippers 10 are actuated by cams 23 carried by the rack bars 16 and so arranged as to actuate the same at the proper time in relation to the movement of the other parts of the mechanism. Arranged below the platen is a sheet 15 supporting device comprising a series of fingers 24 mounted upon a rock shaft 25 and projecting beyond the face of the platen to engage the lower edge of the sheet and support the latter in position in front of the platen. The shaft 25 is provided with a trip finger 26 adapted to be engaged by a plate 27 carried by one of the rack bars 16 to rock the shaft about its axis and move the supporting fingers 24 from beneath the platen, thereby leaving the sheet free to move downward. The details of the construction and operation of the several parts of the feeding mechanism are not necessary to an understanding of the present invention, but a full description of the same will be found in the above mentioned application.

The delivery device of the present application is provided to move the sheet from its printing position, after it has received the impression, and to deliver the same to suitable receiving platform, and it is actuated from the printing mechanism and is timed to operate in synchronism with the other 35 parts of the mechanism. As here shown, this delivery device comprises a series of delivery grippers which are tied together in such a manner that they are caused to operate as a single device. The grippers may 40 be mounted on any suitable support, or frame, which will permit them to have the necessary movement, and in the present construction this frame is shown as comprising a pair of arms 86 which form a swinging frame and are rigidly secured to a shaft 87, which shaft is connected with the shaft 19 in such a manner that rocking movement will be imparted thereto as the racks 16 move up and down. In the present 45 instance, the shaft 87 has secured thereto a sprocket wheel 88 which is connected by means of a sprocket chain 89 with a sprocket wheel 90 secured to the shaft 19. The arms 86 are so shaped that when forward rocking movement is imparted to the shaft 87 the 50 ends of the arms will be carried to positions beneath the platen, and when rearward rocking movement is imparted to the shaft 87, the ends of the arms will be swung rearwardly to a position remote from the platen.

The grippers are carried by the lower ends of the arms 86. In the present construction a bar 91 is rigidly secured to the arms near their ends and is provided with a series of forwardly extending fingers 92 which constitute the fixed jaws of the grippers. Mounted in the arms 86, near the rear edge of the bar 91, is a rod or shaft 93 on which are mounted a plurality of movable gripper jaws 94, there being one of these jaws 70 to coöperate with each finger or fixed jaw 92. Each movable jaw 94 has a rearwardly extending portion, such as a finger 95, which is rigidly secured to the jaw. The rearwardly extending portions, or fingers, 95, 80 of the jaws are tied together by a bar 96 and each finger extends a short distance beyond this bar. Mounted in the arms 86, in the rear of the tie bar 96, is a shaft 97 having rigidly secured thereto a series of 85 fingers 98 corresponding in number and arrangement to the rearwardly extending fingers 95 of the movable gripper jaws. The corresponding fingers 95 and 98 are so arranged with relation to each other that they 90 will be in alinement one with the other when the movable gripper jaws are in a position between their open and closed positions. Consequently, when the jaws are closed, or are fully opened, the fingers 95 and 98 will 95 be out of alinement. A spring 99 is coiled about each pair of fingers, 95 and 98, and is so arranged that its tension will be greatest when the fingers are in alinement, hence the spring will tend to hold the fingers out 100 of alinement on whichever side of the center they may have been moved, thereby holding the jaws either in their open or closed positions, as the case may be. Movement may be imparted to the movable jaws in any suitable 105 manner. As here shown an arm 100 is connected with the movable jaws, preferably by mounting it on the rod or shaft 93 and connecting it with the tie bar 96. By rocking the arm 100 about its axis the 110 movable jaws are moved across their intermediate positions, and their movement is then completed by the springs 99. Any suitable means, such as fixed stops, may be employed to impart rocking movement to the 115 arm 100, and in the present instance an intermediate device is interposed between the arm and its actuating stops. This device comprises a curved arm 120 mounted on the shaft 97 and having one end pivotally connected with the arm 100 in the rear of the tie bar 96. This curved arm extends rearwardly and upwardly and is connected at its upper end, preferably by a pin and slot connection, with an arm 121, which is pivotally mounted and which coöperates with the arm 120 to form a toggle. Preferably, the upper arm 121 of the toggle is mounted on a shaft 122 journaled in bearings carried by the arms 86. Means are provided 120

for imparting rocking movement to the shaft 122, thereby actuating the toggle to open or close the jaws. This rocking movement is controlled by the position of the 5 jaws, and to this end I have, in the present construction, provided the shaft 122 with a trip finger 123 which is arranged between two stops, 124 and 125, carried by one of the bearing brackets 126 for the shaft 87. 10 These stops are so arranged that as the jaws approach the limit of their movement toward the platen, the trip arm 123 will engage the stop 124 and cause the toggle to be operated to close the jaws, and as the 15 jaws approach the limit of their movement away from the platen, the finger 123 will engage the stop 125 to operate the toggle to open the jaws, thus releasing the sheet and allowing it to drop upon a suitable receiving 20 platform or table. The outward or opening movement of the jaws is limited by a suitable controlling device, and in the present instance I have provided the arms 86 with guide pins 127 on which the tie bar 96 is guided and which are provided with nuts 128 arranged to limit the outward movement of the tie bar and hence the opening 25 movement of the jaws.

The operation of the delivery grippers 30 will be readily understood from the foregoing description thereof, and it will be apparent that as the form moves away from the platen the delivery grippers will be moved into a position to receive the sheet 35 and the jaws will be caused to grip the same. As the form-bed completes its outward movement the plate 27 will actuate the supporting devices to release the sheet and as the form again approaches the platen the 40 grippers will swing downward and withdraw the sheet from the platen in advance of the conveying grippers which are moving a new sheet into printing position. As the delivery grippers approach their rearward position, as shown in Fig. 4, trip arm 123 will 45 engage the stop 125 causing the jaws to open and a slight further movement of the grippers moves them out of engagement with the sheet, allowing the same to rest upon the 50 supporting platform. I have shown and described a mechanism in which the jaws are opened and closed as they approach the respective limits of their movement, but it will be understood that the exact time at 55 which these operations take place is unimportant so long as the grippers are in proper position to grip or deliver the sheet.

The mechanism is very simple in its construction and of such a character that it is 60 not liable to get out of order in the normal operation of the press, and it is operated in such a manner as to render the operation positive and to accomplish the same in synchronism with the movement of the other 65 parts of the press and sheet feeding devices.

While I have shown and described one embodiment of my invention I wish it to be understood that I do not desire to be limited to the details thereof as various modifications will occur to a person skilled in the art. 70

Having now fully described my invention, what I claim as new and desire to secure by Letters Patent is:—

1. A sheet delivery device comprising a frame mounted for swinging movement, 75 gripping jaws carried by said frame, a pair of levers pivotally mounted on said frame and connected one to the other and with said jaws and means operated by the swinging movement of said frame to cause said levers 80 to close said jaws as said frame approaches one limit of its movement and to open the same as the frame approaches the other limit of its movement.

2. A sheet delivery device comprising a 85 frame mounted for swinging movement, gripping jaws carried by said frame, an arm operatively connected with said jaws, and an actuating device mounted on said frame and operated by the swinging of said frame 90 to cause said arm to operate to close said jaws as said frame approaches one limit of its movement and to open said jaws as said frame approaches the other limit of its movement. 95

3. A sheet delivery device comprising a frame mounted for swinging movement about a fixed axis, gripping jaws carried by said frame, an actuating device for said jaws comprising a lever mounted on said frame, 100 and a trip arm connected with said lever, and stops mounted adjacent to the path of said frame to engage said trip arm and cause said lever to close said jaws as the frame approaches one limit of its movement, 105 and to open said jaws as the frame approaches the other limit of its movement.

4. A sheet delivery device comprising a frame mounted for swinging movement, a 110 jaw carried by said frame at a point remote from its axis, a movable jaw mounted on said frame to coöperate with the first jaw, and an actuating device comprising a pair of levers pivotally mounted on said frame and connected one with the other and with 115 said movable jaw and means controlled by the movement of said frame to cause said levers to move said movable jaw toward and away from said first jaw.

5. A sheet delivery device comprising a 120 movable supporting frame, a jaw carried by said frame, a second jaw pivotally mounted on said frame to coöperate with the first-mentioned jaw, an actuating device comprising a lever connected with said pivotal jaw, 125 a trip arm connected with said lever, and fixed stops arranged to respectively engage said trip arm according to the direction of the movement of said supporting frame, whereby the movement of said frame will 130

cause said jaws to be opened and closed in timed relation to said movement.

6. A sheet delivery device comprising a supporting frame mounted for swinging movement about a fixed axis, a jaw carried by said frame at a point remote from said axis, a second jaw pivotally mounted on said frame to coöperate with the first-mentioned jaw, an actuating arm connected with said pivotal jaw, and means to impart movement to said actuating arm to cause said pivotal jaw to be moved into its open or closed position, said means comprising a part mounted on said frame independently of said arm and controlled by the movement of said frame.

7. A sheet delivery device comprising a supporting frame mounted for swinging movement, a jaw carried by said frame at a point remote from said axis, a second jaw pivotally mounted on said frame to coöperate with the first-mentioned jaw, an actuating device for said pivotal jaw comprising an arm connected with said pivotal jaw, and a trip arm connected with the first-mentioned arm, and fixed stops arranged adjacent to the path of said frame to engage said arm and actuate said pivotal jaw.

8. A sheet delivery device comprising a supporting frame mounted for swinging movement, a jaw secured to said frame at that end opposite its axis, another jaw pivotally mounted on said frame to coöperate with the first jaw, a pair of pivotally connected levers mounted on said frame, one of said levers having operative connection with said pivotal jaw, a trip arm connected with the other of said levers, and fixed stops arranged to engage said trip arm to cause said pivotal jaw to be operated when said frame is near the limit of its movement in either direction.

9. A delivery device comprising a supporting frame mounted for swinging movement, jaws carried by said frame at a point remote from its axis, one of said jaws being mounted for movement relatively to the other, a lever pivotally mounted on said frame adjacent to said jaws and operatively connected with said movable jaw, a second lever pivotally mounted on said frame at a point near the axis thereof and operatively connected with the first-mentioned lever, a trip arm connected with said second lever, and a stop arranged to be engaged by said arm as the frame moves from one position to another and to cause said movable jaw to be actuated.

10. A sheet delivery device comprising a supporting frame mounted for swinging movement, a fixed jaw secured to said frame at a point remote from its axis, a second jaw pivotally mounted on said frame to coöperate with the first jaw, an arm connected with said pivotal jaw, a lever pivotally mounted

on said frame between its ends and having one end operatively connected with said actuating arm, a second lever pivotally mounted on said frame adjacent to its axis and operatively connected with said first-mentioned lever, a trip arm connected with said second lever, and stops arranged to be engaged by said trip arm as said frame moves toward the respective limits of its movement in either direction.

11. A sheet delivery device comprising a supporting frame mounted for swinging movement, a bar secured to said frame at that end opposite said axis and having parts constituting jaws, pivotal jaws mounted on said frame adjacent to said bar, a trip arm mounted on said frame near its axis, and pivotally connected levers mounted on said frame and connected respectively with said pivotal jaws and said trip arm, and fixed stops arranged to engage said trip arm and cause said pivotal jaws to be operated when said frame is near the limit of its movement in either direction.

12. In a sheet delivery device, a frame, a jaw mounted on said frame, a second jaw pivotally mounted on said frame to coöperate with the first jaw, a finger mounted on said frame, a second finger rigidly connected with said pivotal jaw and arranged to be in alignment with the first mentioned finger when said jaw is in position between its closed position and its fully open position, a spring coiled about said fingers, and an actuating device to move said pivotal jaw across said intermediate position.

13. In a sheet delivery device, a frame, a jaw mounted on said frame, another jaw pivotally mounted on said frame to coöperate with the first jaw, said pivotal jaw having a rearwardly extending finger, a finger mounted on said frame, held against longitudinal movement and arranged to be in alignment with the finger of said pivotal jaw when the latter is in a position between its closed position and its fully open position, and a spring coiled about said fingers.

14. In a sheet delivery device, a frame mounted for swinging movement, a plurality of jaws carried by said frame at a point remote from its axis, a shaft journaled in said frame adjacent to said jaws, a plurality of jaws carried by said shaft and arranged to coöperate with the first-mentioned jaws, an arm connected with said shaft, a trip arm mounted on said frame at a point remote from said shaft, an operative connection between said arms, and stops to engage said arm as said frame moves from one position to another.

15. In a sheet delivery device, a frame mounted for swinging movement, a plurality of jaws carried by said frame, a plurality of other jaws pivotally mounted on said frame and arranged to coöperate with

said first-mentioned jaws, means to connect said pivotal jaws one to the other to cause them to operate simultaneously, an actuating arm to impart movement to said pivotal jaws, a trip arm connected with said actuating arm, and stops arranged to be engaged by said trip arm as said frame moves from one position to another.

16. In a sheet delivery device, a frame
10 mounted for swinging movement, a plurality
of jaws carried by said frame, a shaft
journalized in said frame adjacent to said
jaws, a plurality of jaws carried by said
shaft and arranged to coöperate with the
15 first mentioned jaws, an arm pivotally sup-
ported by said frame and having one end
connected with said shaft, a second arm car-
ried by said frame and connected with the
first named arm, a trip finger connected with
20 said second arm, and stops arranged to be
engaged by said trip finger as said frame
moves from one position to another.

17. In a sheet delivery device, a supporting shaft, means for imparting rocking movement to said shaft, a supporting frame rigidly secured to said shaft, a bar mounted on that end of said frame remote from said shaft and having parts constituting jaws, a plurality of jaws pivotally supported by said frame near the first jaws, said pivotal jaws being rigidly connected one to the other to cause them to move simultaneously, an arm pivotally mounted on said supporting frame and having one end connected with 30 said pivotal jaws, a second arm mounted on said frame and having a slotted connection with that arm which is connected with the pivotal jaws, a tripping finger connected with the last-mentioned arm, and fixed stops 35 arranged to engage said finger and cause the operation of said pivotal jaws.

18. In a sheet delivery device, a supporting shaft, means for imparting rocking movement thereto, a supporting frame rigidly secured to said shaft, a transverse bar mounted on that end of said frame remote from said shaft and having forwardly extending parts constituting jaws, a shaft mounted on said frame in the rear of said bar, a plurality of jaws mounted on said shaft for pivotal movement toward and away from the first mentioned jaws, each of said pivotal jaws having a part extending rearwardly from its axis, a bar rigidly connected with each of said rearwardly extending parts, a lever mounted on said frame and connected with the pivotal jaws, a trip arm connected with said lever, stops to actuate said trip arm as the said frame approaches the limit of its movement in either direction, and a resilient device to hold said pivotal jaws in either their open positions or their closed positions.

19. In a sheet delivery device, a supporting shaft, means for imparting rocking

movement thereto, a supporting frame rigidly secured to said shaft, a bar secured to that end of said frame remote from said shaft and having forwardly extending parts constituting jaws, a shaft mounted on said frame in the rear of said bar, jaws mounted on said shaft for movement toward and away from the first mentioned jaws, each jaw having a rearwardly extending part, a tie bar rigidly secured to the rearwardly extending parts of the several jaws between their rear ends and their axes, a second shaft mounted on said frame in the rear of said tie bar, fingers rigidly secured to said last-mentioned shaft and arranged normally out of alinement with the rearwardly extending parts of the corresponding pivotal jaws and adapted to be moved from one side of their alined position to the other side thereof by the movement of said pivotal jaws, springs coiled about the corresponding fingers and rearwardly extending parts of said pivotal jaws, a lever mounted on said frame and connected with said pivotal jaws, a trip arm connected with said lever, and stops arranged to engage said trip arm and actuate said lever as said frame approaches the limit of its movement in either direction.

20. In a sheet delivery device, a shaft, a frame rigidly secured to said shaft, jaws 95 carried by said frame at a point remote from said shaft, a shaft journaled in said frame, jaws carried by said last-mentioned shaft and arranged to coöperate with the first-mentioned jaws, an actuating device comprising two levers pivotally mounted on said frame and having their adjacent ends connected, one of said levers being connected with the last-mentioned shaft, a trip finger 100 connected with the other of said levers, and 105 stops to engage said trip finger to cause the device to be actuated as said frame approaches the limit of its movement in either direction about the axis of said shaft.

21. In a sheet delivery device, a supporting shaft, means for imparting rocking movement thereto, a frame secured to said shaft and having its end portion extending at substantially right angles to the body portion thereof and arranged to be moved from a substantially horizontal position to a substantially vertical position by the rocking movement of said shaft, gripping devices carried by the end portion of said frame, and means for automatically actuating said gripping devices. 110 115 120

22. In a printing-press, comprising a frame, a platen carried thereby, and a form-bed movable toward and from said platen, a rock shaft mounted on said frame, a gripper frame carried by said rock shaft, gripping jaws carried by said gripper frame, an actuating device for said gripping jaws, means controlled by the movement of said gripper frame about the axis of said shaft to operate 125
130

said actuating device, and an operative connection between said rock shaft and said form-bed.

23. In a printing press, comprising a main frame, a normally stationary platen carried by said main frame, and a form-bed movable in a right line toward and from said platen, a shaft journaled in said main frame, a connection between said shaft and said form-bed to cause rocking movement to be imparted to the former by the reciprocatory movement of the latter, a gripper frame carried by said shaft and having a portion remote from said shaft extending at an angle to that portion thereof which is con-

nected directly with said shaft, the end of said angularly extending portion being arranged to be moved to a position adjacent to the lower edge of said platen when said rock shaft has moved in one direction, gripper jaws carried by said angularly extending portion of said frame and means actuated by the movement of said gripper frame to cause said jaws to be closed at a point adjacent to said platen and to be opened at a point remote from said platen.

In testimony whereof I hereunto affix my signature.

EMERSON P. JENNINGS, JR.
